UNITED STATES PATENT OFFICE.

FREDERICK W. HURST, OF LOGAN, UTAH.

IRONING-BOARD STRUCTURE.

Application filed April 6, 1923. Serial No. 630,291.

The present invention relates to stationary ironing boards which are built into the wall of a room so as to be entirely concealed when not in use.

5 The main object of the invention is to provide an ironing board of this character that will open outwardly from the frame or cabinet in the wall and may be turned in any horizontal direction parallel with or at 10 right angles to the wall when open.

A further object of the invention consists in providing a secondary or sleeve board attached to the main board in such a manner that it can be placed above the latter 15 when open and folded beneath the same when in closed position.

Still another object of the invention resides in the fact that no leg or support for the ironing board is needed for resting it 20 on the floor, but that instead a prop is provided which is situated within the frame or cabinet. This prop is so constructed that it falls automatically in position when the door of the cabinet is opened and closes 25 with the shutting of the door. The advantage of this construction is that less depth is required in the cabinet for housing the ironing board.

One embodiment of the invention is illustrated in the accompanying drawings—

Figure 1 shows the ironing board in side view and open position with the cabinet in section;

Figure 2 shows the ironing board in 35 closed position and the frame or cabinet in perpendicular section;

Figure 3 is a horizontal section of the cabinet with the ironing board open;

Figure 4 is a fragmentary longitudinal 40 section of the ironing board;

Figure 5 is a top plan view of the supporting member for the ironing board, and

Figure 6 is a perspective view of some 45 details.

Referring particularly to Figures 1, 2 and 3, the reference numeral 10 represents a wall having a recess into which a frame or cabinet 11 is built in so as to fit tightly on all sides of the recess. Near the bottom 50 of the frame is secured a transverse slat 12 running the entire width across the frame and to this slat is hinged, as at 13, a flap or bracket 14 which is comparatively short and only protrudes a short distance beyond 55 the wall when in open position. This bracket has a rearward extension 15 which

abuts on the under side of the slat 12 when the bracket is open so as partly to support the bracket on the slat.

Resting on the bottom of the frame is 60 a prop or strut 16 which is preferably loose in the frame and has its lower end disposed in engagement with the front edge of an abutment 1' secured to the bottom of the cabinet. This strut reaches upwardly and 65 terminates with a cross piece 18 extending the full width of the bracket 14 and adapted to engage in a groove 19 provided on the under side of the bracket. As seen in Figure 1, this strut stands at a slight inclination when engaging with the groove 19 and is for that purpose beveled on its bottom edge, as at 20. In folded position, as seen in Figure 2, the strut is held perpendicularly by the abutment 1' and its cross piece 70 18 falls into the recess formed near the ledge 15 of the bracket.

On the upper side of the bracket is provided a mounting for an ironing board. This mounting includes a track consisting 80 of an arcuate metal plate or strip 22 which preferably is semi-circular and has a rabbet formed along its circular edge 23 by placing spacing boards or blocks 27 between it and the bracket to which it is secured by screws. The blocks 27 cooperate to form the inner 85 section of a support for the track strip. In the rabbet of the track strip is engaged the flange 24 at the lower end of the channel iron or cleat 25 secured by means of 90 screws or in any other suitable manner to the rear end of the main ironing board 26. The outer end of the bracket 14 has secured thereto a filler piece or block 21 in order to maintain the bracket and the ironing 95 board 26 in parallel relation at all times.

At the sides of its inner end portion the block 21 which may be termed the outer section of the support for the track strip 100 is formed with recesses or seats 21' to receive the ends of the track strip and maintain the upper faces of the strip 22 and block 21 in the same plane. This construction is best seen in Figure 4 where also a pintle 48 is shown, around which the main ironing board 26 is permitted to be turned out of its normal position. When the main ironing board, as seen in Figure 3, points 105 outwardly at right angles from the wall, the channel 25 engages entirely by means of its flange 24 with the protruding plate 22. When it is desired to turn the main 110

ironing board out of its central position, the flange 24 will then run in the rabbet 23 so as to still engage therein.

At the extreme end of the main ironing board 26 is provided a downwardly extending hinge member 28 rigidly secured to the end of the main board by means of screws 29 or the like. A pair of parallel links 30 are journaled on their transverse portion 31 at the lower end of the hinge member 28 so as to be able to swing from a perpendicular position down to a horizontal one below the ironing board 26. These links 30 have journaled connection 21 at one end of a secondary ironing board 32 and a second pair of links 33 extending in parallel direction with the first links 30 are also journaled under the secondary board 32, as at 34. The short or second links 33 have at their lower ends a connecting band 35 journaled thereto, as at 36, the other end of the band being similarly journaled, as at 37, about midway down on the first links 30. By referring to Figure 1, it will be seen that with the secondary ironing board 32 in open position, the connecting band 35 will lie flat on top of the main ironing board 26 and the links 30 and 33 will form legs for supporting the secondary ironing board 32 in spaced relation on top of the main ironing board. When the secondary ironing board is not in use or when the boards are to be folded in the cabinet or frame, the secondary ironing board 32 is swung around the pin 31 until it lies flat beneath the main ironing board 26, as best seen in Figure 2, and in order to hold the secondary ironing board in this position, a small latch 38 is provided on the under side of the main ironing board. This latch is preferably a swiveled nut which may be turned to engage the head of the secondary ironing board when locking the same.

Behind the hinge plate 28 at the free end or the ironing board 26 is furnished a recess 45 in which the head plate 46 is seated to keep the secondary board locked in erected position. This plate is secured on the under side of the band 35 in such a manner that its ledge 45 engages behind the edge of the plate 28.

A door 40 hinged to one side of the frame 11 is intended to close the opening of the frame 11 and in doing so will hold the boards in upright position in the frame and entirely concealed behind the door. On the inner side of the door may be mounted to turn one or more clothes racks 41 which can be turned outwardly when the door is open to provide a place for clothes to dry when the ironing board is in use.

The main ironing board is balanced and hung in the frame so that, directly the door 40 is swung open, the ironing board will fall outwards until the ledge 15 strikes the slat 12. Simultaneously the strut 16 will also

fall outwardly and engage in the groove 19 on the under side of the turntable 14, and in this manner firmly support the turntable as well as the ironing boards. If the secondary ironing board or sleeve board 32 is required, it will be released from its latch 38 and swung outwardly on top of the main ironing board and in case it is found more convenient to have the main ironing board running parallel or at any other angle with the wall, it is swung to one side, as shown by dotted lines in Fig. 3. This may be done not only for gaining space but may also be required to obtain better light during ironing.

Having thus described the invention, what is claimed as new is:—

1. In a folding ironing table construction, a frame, a bracket pivotally mounted in said frame and adapted to be swung out of the frame to a substantially horizontal position, a mounting for an ironing board carried by said bracket and comprising a support including an outer section having a flat upper face and having recesses at the sides of its inner end portion forming seats, an inner section of less depth than the outer section, and an arcuate track strip secured upon said inner section with its end portions secured in the seats formed in the inner end portion of said outer section and its upper face flush with the upper face of the outer section, said track strip having its outer peripheral edge portion projecting beyond said inner section, an ironing board resting upon the flat upper faces of said track strip and outer section of said support and pivotally connected with said outer section at the center of curvature of said track strip, and a depending cleat secured to the inner end of said ironing board and engaged beneath the projecting peripheral edge portion of the track strip. 100

2. In a folding ironing table construction, a frame, a bracket pivotally mounted at one end in said frame and adapted to be swung downwardly out of the frame to a substantially horizontal position, a filler block secured upon the upper face of the outer end portion of the bracket and having a flat upper face, an arcuate track strip disposed over said bracket with its ends secured to the inner end of said block and its upper face flush with the upper face of the block, a spacing block for said track strip extending from the inner end of said filler block beneath said track strip and having an arcuate edge face terminating short of the outer arcuate edge of the track strip, an ironing board having its butt end portion overlapping said bracket and resting upon said filler block and track strip and having an arcuate inner end edge face, means pivotally mounting said ironing board for swinging transversely of the bracket, and a depending cleat carried by the butt end of said ironing

board and at its lower end having a projection extending beneath the overhanging peripheral edge portion of the track strip.

3. In a folding ironing table construction, 5 a cabinet open at its front, a slat extending across said cabinet in spaced relation to its bottom, an abutment in the bottom of said cabinet, a bracket hinged to said slat and adapted to be swung downwardly out 10 of the cabinet and at its inner end having a lip extension of reduced thickness to engage the under face of said slat and limit downward movement of the bracket, a prop in said cabinet having its lower end seated

upon the bottom of the cabinet in engagement with said abutment and its upper end portion formed with a bill of reduced thickness adapted to overlap said lip when said bracket is disposed vertically in the cabinet and engage in a seat formed in the under 20 face of the bracket when the bracket is swung downwardly out of the cabinet, and an ironing board carried by said bracket for movement into and out of the cabinet 25 with the bracket.

In testimony whereof, I affix my signature.

FREDERICK W. HURST. [L.S.]
